INVENTOR:

Howard H. York,
By Frank H. Horner.

ATTORNEY.

UNITED STATES PATENT OFFICE.

HOWARD H. YORK, OF LOGANSPORT, INDIANA.

WATER-SUBMERGED AIR-CHAMBER FOR WATER-PIPES.

1,342,491.

Specification of Letters Patent.

Patented June 8, 1920.

Application filed July 14, 1919. Serial No. 310,700.

To all whom it may concern:

Be it known that I, HOWARD H. YORK, a citizen of the United States, residing at Logansport, in the county of Cass and State 5 of Indiana, have invented certain new and useful Improvements in Water-Submerged Air-Chambers for Water-Pipes, of which the following is a specification.

This invention relates to a device for cushioning hydraulic impacts in water pipes, being an improvement on my former U. S. Letters Patent No. 1,216,761 issued Feb. 20, 1917; and one of the objects of the present invention is to provide a more sensitive and efficient device for absorbing hydraulic impacts than obtains in my former patent.

A further object of the invention consists in the provision of a device of the above 20 character wherein a number of chambers are submerged within the water, said chambers being arranged at different distances from the main water line and adapted to hold a quantity of air, and all of said chambers having air communicating passageways between them so that hydraulic impacts are gradually absorbed without jar and noise.

A still further object of the invention 30 consists in the provision of a device of the above character in which the loss of air may be easily replaced, when necessary.

I accomplish the above objects of the invention, and such others as may appear 35 from a perusal of the following description and claims, by means of the construction illustrated in the accompanying drawings, forming a part hereof, in which—

Figure 1 is a central vertical sectional view through the tank, the air holding chambers being shown in elevation. Fig. 2 is a horizontal section through the tank, on the line 2—2 in Fig. 1. Fig. 3 is a perspective view of one of the air holding chambers or cups, the remaining parts of the device being omitted. Fig. 4 is a fragmentary detail view in side elevation of one of the cups, showing the means for supporting in operative position.

Referring to the drawings, 10 represents a water service pipe for conducting the water to the points of consumption. Interposed in service pipe 10 at a suitable point is a lateral pipe 11 which communicates 55 with tank 12, the latter being closed at the top and open at the bottom for the intro-

duction of the internal parts into the hollow chamber 13. The lower and open end of tank 12 is closed by means of a plate 15 which is secured to the annular flange 16 60 of tank 12 by means of the bolts 17.

Arranged centrally within the hollow portion of tank 12 is a series of uniformly spaced air holding inverted cups 20 which are arranged *seriatim* in a vertical plane. 65 Cups 20 are retained in position relatively to one another by means of a plurality of vertically disposed rods 21 and screws 22 which pass through apertures 23 in said rods and enter threaded apertures 24 in the 70 integral ears 25 depending from the lower edges of cups 20. Each of the supporting rods is provided with a plurality of spaced apertures 23 to enable cups 20 to be spaced a greater or less distance apart, and rods 21 75 are held in spaced relationship by introducing their upper ends into sockets 27 in the closed end of cups 20 and their lower ends into sockets 28 in plate 15.

In practice, the hollow portion or chamber 80 13 of tank 12 and cups 20 is full of air when the device is introduced into the service pipe 10. When the water is turned on tank 12 will fill with water and the air in cups 20 will be placed under compression. 85 The hollow portion confining the air in one cup communicates with the air chamber of the next cup by means of a pipe 30, whereby direct communication is established between the air holding chambers of all the cups, so 90 that shock of impact delivered by the back pressure, as when the flow of water at a faucet is suddenly discontinued, is absorbed by the cushioning effect of the air confined in the various cups 20.

I have found in practice, that the present device is far more sensitive and the effect of impact, induced by back pressure, is more effectively absorbed when delivered to air confined in a plurality of distinct air holding chambers or pockets arranged more or less remotely from the point of egress of the back pressure in the tank, so that air in the pockets will be affected alternately, than obtained in my former device where 105 the impact was delivered upon the air contained in a single pocket, it being immaterial whether the surface area of the single pocket equaled the combined surface area of several pockets in the present device.

Loss of air below the normal requirement 110 for the efficient operation of the device may

be replaced through the filling pipe 32 which is provided with a stop-cock 33. Filling pipe 32 passes through plate 15 and projects into the hollow chamber in lower 5 cups 20. The hollow chambers of cups 20 are connected by means of the communicating pipes 30, so that all chambers of cups 20 may be supplied with air introduced through filling pipe 32.

10 The device is also provided at the bottom with a drain-cock 35 through which the water in chamber 13 and the interior of pipe 10 may be drained when it is found desirable to do so.

15 Having thus fully described my said invention, what I desire to secure by Letters Patent, is—

1. The combination with a water service pipe, of a closed water tank having its interior in communication with the interior of the service pipe, and a plurality of spaced air tanks arranged *seriatim* and submerged within the water tank, and a pipe extending from outside the water tank and into the 25 interior of the air tanks for introducing air into the latter.

2. The combination with a water service pipe, of a closed water tank having its interior in communication with the interior of the service pipe, and a plurality of spaced air tanks arranged *seriatim* and in a plane parallel with the inlet to said water tank for alternately checking the impact of back pressure.

35 3. The combination with a water service pipe, of a closed water tank having its in-

terior in communication with the interior of the service pipe, a plurality of spaced air tanks arranged *seriatim* and in a plane parallel with the inlet to said water tank 40 for alternately checking the impact of back pressure, and means for supporting the air tanks in determined relationship to one another within the water tank.

4. The combination with a water service 45 pipe, of a closed water tank having its interior in communication with the interior of the service pipe, a plurality of spaced air tanks arranged *seriatim* within the water tank and in a plane parallel with the inlet 50 to said water tank for alternately cushioning the effect of back pressure, means for supporting the air tanks in determined relationship to one another within the water tank, and means for filling all of the air 55 tanks from a common air supply source.

5. The combination with a water service pipe, of a closed water tank having its interior in communication with the interior of the service pipe, a plurality of air tanks 60 spaced apart and arranged *seriatim* within the water tank and in advance of the water inlet therein, supports for mounting the air tanks, means for securing the air tanks to the supports, and means for introducing air 65 into the interior of the air tanks.

In witness whereof I have hereunto set my hand and seal at Logansport, Indiana, this 2nd day of July, A. D. one thousand nine hundred and nineteen.

HOWARD H. YORK. [L. S.]
